UNITED STATES PATENT OFFICE.

JOHN M. DAVIDSON, OF ALLEGHENY, PENNSYLVANIA.

DESIGN FOR A WASHBOARD.

SPECIFICATION forming part of Design No. 32,711, dated May 22, 1900.

Application filed April 27, 1900. Serial No. 14,631. Term of patent 14 years.

To all whom it may concern:

Be it known that I, JOHN M. DAVIDSON, a citizen of the United States, residing at Allegheny, in the county of Allegheny and State 5 of Pennsylvania, have invented and produced a new and original Design for Washboards; and I do hereby declare the following to be a full, clear, and exact description of the invention, such as will enable others skilled in the 10 art to which it appertains to make and use the same.

Figure 1 is a front elevation of a washboard, showing my new design; and Fig. 2, an edge view of the same.

15 As shown in the drawings, the leading feature of my design consists of a transversely-

corrugated body A, semicircular at its lower end and inclosed in a frame B, which extends above the body, is bent inward from both sides, and is provided with a handle C.

20

Having described my invention, what I claim as new, and desire to secure by Letters Patent, is—

The design for a washboard, substantially as herein shown and described.

25

In testimony whereof I affix my signature in presence of two witnesses.

JOHN M. DAVIDSON.
